ROY O. WERTZ, OF CLEVELAND, OHIO, ASSIGNOR TO THE OHIO ELECTRIC MANUFACTURING CO., OF CLEVELAND, OHIO, A CORPORATION OF OHIO

MEANS FOR CONVEYING MAGNETIC MATERIAL

Application filed May 9, 1929. Serial No. 361,559.

This invention relates generally to the art of conveying magnetic material, such for example, as elongated iron or steel articles. It is particularly concerned with a new and improved method of conveying elongated magnetic articles and with a new and improved mechanism for conveying such articles.

In the art of conveying elongated magnetic articles such as iron or steel in sheets, strips or other forms or shapes, it has been proposed to employ a hollow rotatable cylinder of non-magnetic material on which the article rested while being conveyed and to mount a magnet 15 in the cylinder. The magnet was intended to attract the article and hold it against the cylinder with little or no slippage while the cylinder rotated and carried the article along to the next roller. In practice, however, the 20 apparatus has not been entirely satisfactory.

I have discovered that when the cylinder is made of sufficient thickness to stand the loads imposed on it, the air gaps between the poles of the magnet and the articles 25 were so great that the resultant attractive force on the latter was smaller than desired for most efficient operation. The spaces intervening between the poles and the article consist in part of the non-magnetic material 30 of the shell and in part of open air but from a magnetic conducting standpoint all the intervening distances may be considered as air gaps because the non-magnetic shell is little if any better than open air as a conductor.

35 I have discovered how to make such prior apparatus highly efficient and satisfactory and how to convey elongated metallic articles positively and cheaply by magnetic means.

40 In the drawings accompanying and forming a part of this specification

Fig. 1 is a longitudinal central vertical sectional view of one form of apparatus embodying my invention;

45 Fig. 2 is a transverse section taken on line 2-2 of Fig. 1;

Fig. 3 is a fragmentary top plan view of the apparatus of Figs. 1 and 2.

In the drawings the conveying roll is made 50 up of a rotating shell and a stationary mag-

net carrier. The rotating shell 1 is cylindrical in shape with one end closed by disc 2 which is united to a shaft 3. The shaft 3 is supported in bearings (not shown) adjacent to disc 2 and may be provided with means for 55 driving it (also not shown). It will be understood that in a long conveyor, some of the rollers will be idlers and some will be driven.

The magnet carrier shown comprises a shaft 4 provided with a disc 5 adjacent to the 60 shaft supporting means (not shown), the disc 5 preferably being of such size that it will have a good bearing fit in the open end of shell 1. Any type of bearing can be substituted for the plane bearing shown. The 65 shaft 4 carries beyond disc 5 an open topped box-like extension 6 which extends for substantially the full inside length of shell 1. This extension has an upstanding partition 7 disposed centrally in and spaced substantially equidistant from the side walls 8 and end walls 9 of the box-like member 6. In the spaces between partition 7 and walls 8 and 9 electric windings 10 are placed and have lead out connections through shaft 4. The 70 upper edges of walls 7, 8 and 9 are shaped to conform to and lie closely adjacent to the interior wall of shell 1.

When electric current flows in the windings 10 the magnet will be energized and 80 lines of force will extend from the central pole 7 to the side poles 8 and also to the small end poles 9. These lines of force are, by my invention, made to pass directly through the shell in concentrated form and into the superimposed magnetic article 12 and then back 85 through the shell to the opposite pole.

The shell 1 which is composed of non-magnetic material is provided with means to concentrate the magnetic lines of force extending between the poles 7 and 8 of the magnet, and greatly shorten the air gap between the poles and article being conveyed so that the lines of force will exert a strong pull on the article toward the poles 7 and 8. This means is shown in the form of a plurality of pieces 90 11 of magnetic material extending through the walls of shell 1. These pieces 11 can, of course, be of various shapes, lengths and sizes and may be cast in place or inserted in 95 100

holes provided therefor. The amount of magnetic pull which can be exerted on a magnetic article on shell 1 will depend to a considerable extent on the number, size and disposition of pieces 11 and the pull desired will thus determine largely the size and number of the pieces 11 in any specific instance. These pieces also concentrate the lines of force and since they extend radially of the shell, serve to prevent any short circuiting of the lines of force as would be possible if the pieces 11 extended circumferentially or axially of the shell.

When the shell 1 with pieces 11 is used and current passes through windings 10 the lines of force will be concentrated in the pieces 11 and hence will extend through shell 1 where they can enter a magnetic article on shell 1 in such numbers as to exert a strong pull on the article against the shell.

By a magnetic material or article is meant one capable of being attracted by a magnetic force.

Having thus described my invention so that others may be enabled to practice the same what I desire to secure by Letters Patent is set forth in what is claimed.

What is claimed is:

1. A conveyor for elongated magnetic articles which comprises a stationary multipolar magnet extending transversely to the direction of travel of the articles, and a non-magnetic shell rotatable about the magnet for conveying the articles, the shell having means for concentrating the magnetic lines of force at the outside surface of the shell and above the poles of the magnet.

2. A conveyor for elongated magnetic articles which comprises a stationary multipolar magnet extending transversely to the direction of travel of the articles, and a non-magnetic shell rotatable about the magnet for conveying the articles, the shell having means for passing lines of force therethrough in concentrated condition.

3. A conveyor for elongated magnetic articles which comprises a stationary multipolar magnet extending transversely to the direction of travel of the articles, and a non-magnetic shell rotatable about the magnet for conveying the articles, the shell having a plurality of pieces of magnetic material disposed therein to concentrate the magnetic lines of force.

4. A conveyor for elongated magnetic articles which comprises a stationary multipolar magnet extending transversely to the direction of travel of the articles, and a non-magnetic shell rotatable about the magnet for conveying the articles, the shell having a plurality of pieces of magnetic material disposed therein and adapted to decrease the air gap between the poles and the article being conveyed.

5. A conveyor for magnetic articles which

comprises a stationary multipolar magnet extending transversely of the direction of travel of the articles and a non-magnetic shell rotatable about the magnet for conveying such an article thereon, said shell having in it portions of magnetic material so disposed as to decrease the resistance to the flow of magnetic lines of force from the poles of the magnet to and from the article and to concentrate said lines of force, the said portions being so disposed as to compel travel of the lines of force through said article.

6. A conveyor for magnetic material comprising a hollow non-magnetic roll, means within the roll for establishing a magnetic field including that part of the said material in contact with the roll, and radial inserts of permeable material in the roll for carrying the flux between said material and said means.

7. A hollow roll of non-magnetic material having particles of permeable material therein and means for causing lines of magnetic force to be set up in said particles.

8. A hollow roll of non-magnetic material having radial inserts of permeable material therein and means for causing lines of magnetic force to be set up in said inserts.

9. A hollow roll of non-magnetic material having particles of permeable material therein, and means within the roll for establishing a magnetic field.

10. A conveyor for magnetic material comprising a hollow non-magnetic roll having a plurality of pieces of magnetically permeable material disposed therein, and means within the roll for establishing a magnetic field.

11. A conveyor for magnetic material comprising a hollow non-magnetic roll having a plurality of radial inserts of permeable material disposed therein, and a magnet within the roll.

In testimony whereof I hereunto affix my signature this 24th day of April, 1929.

ROY O. WERTZ.
